CARBURETOR

Albert H. Winkler, Elmira, N. Y., assignor to
Bendix Aviation Corporation, South Bend, Ind.,
a corporation of Delaware

Application March 7, 1950, Serial No. 148,198

10 Claims. (Cl. 123—127)

1

The present invention relates to carburetors for internal combustion engines, and more particularly to carburetors of the multiple stage type for automotive engines.

In the operation of a multiple stage carburetor having primary and secondary induction systems, only the primary system is employed at lower engine speeds so that relatively high air velocities will be maintained in the induction passage to give a greater effective suction for fuel delivery and thus a more positive control over fuel metering and distribution during the period of relatively low air flow. With the acceleration of the engine to the higher speed ranges, the secondary induction system becomes operative to increase the volume of fuel-air delivery sufficiently to obtain maximum power output and speed of the engine. The present invention is principally concerned with a mechanism for controlling the secondary induction system in response to throttle position in the primary induction system and to the temperature of the engine, one of the objects of the invention being to provide a temperature responsive means for rendering the control mechanism ineffective to actuate the secondary system until the engine has reached a predetermined temperature.

Another object of the invention is to provide a carburetor having a primary and a secondary induction system wherein the secondary system is controlled in response to throttle position in the primary system and is brought into operation gradually as the engine accelerates.

Another object of the invention is to provide, in a multiple stage carburetor having a mechanism controlled in accordance with the movement of throttle valve in the primary system for controlling the throttle valve of the secondary system, a temperature responsive means for positively preventing the secondary throttle valve from operating while the engine is cold.

Another object is to provide in a multiple stage carburetor of the aforesaid type a mechanism for delaying or retarding the operation of the secondary throttle valve until the engine has had time to respond to the increased opening of the primary throttle valve.

Still another object of the invention is to provide a carburetor having primary and secondary induction systems with a choking device in the primary system, wherein the secondary system remains ineffective while the choking device is effective.

Additional objects and advantages will become

2

apparent from the following description and accompanying drawings, wherein:

Figure 1 is a side elevation of a multiple stage carburetor showing certain elements of the control mechanism for the secondary induction system in cross-section;

Figure 2 is a partial side elevation of a multiple stage carburetor showing portions of the control mechanism of the secondary induction system in cross section as in Figure 1, but in a different operative position; and

Figure 3 is a view of certain levers forming a part of the control mechanism.

Referring more specifically to the drawings, and 15 to Figure 1 in particular, a multiple stage carburetor generally designated by numeral 10 is shown mounted on an intake manifold 12 of an internal combustion engine (not shown) and contains a primary induction system 14A and a secondary induction system 14B, including induction passages 18A and 18B, throttles 20A and 20B and main discharge jets 22A and 22B, respectively. The two systems are provided with separate idle systems, fuel inlet valves and float chambers and 20 are adapted to discharge the fuel-air mixture directly into intake manifold 12. A single accelerating pump (not shown), which may be either a mechanical or a vacuum type pump, is adapted to discharge into the primary induction system 25 as the primary throttle is opened. In the present carburetor only the primary induction system is controlled by a choke valve 24, preferably of the unbalanced type, mounted in the air inlet of the induction passage 18A on a shaft 26, said 30 choke valve being controlled either by a manual means or by an automatic choking device having a thermostatic element and a vacuum actuated means.

The throttle valve 20A of the primary induction system is manually actuated by the operator through lever 30 mounted on one end of throttle shaft 32 and is regulated in the degree of closing by a stop screw 34 on said lever and a fast idle cam 36 controlled through a linkage (shown in 35 part at 37) by a choke control mechanism (not shown). The throttle valve 20B of the secondary induction passage is controlled by the primary throttle valve through a linkage consisting of a lever 38 rotatably mounted on one end of shaft 32, a lever 40 rigidly mounted on one end of throttle shaft 42 of the secondary throttle valve 20B and a rod 44 interconnecting levers 38 and 40, said rod being pivotally connected to the free 40 end of lever 38 and to lever 40 by a trunnion 46 through which said rod is adapted to slide. The

force tending to open the secondary throttle valve as the primary throttle valve is opened is transmitted from rod 44 through a coil spring 48 mounted on said rod and reacting between a fixed collar 50 and trunnion 46. Lever 38 is actuated in the direction to open the secondary throttle valve by lever 30 through a one-way connection consisting of a lug 52 on lever 38 adapted to be engaged by lever 30 as said latter lever is moved in the opening direction. The position of lever 38 in relation to lever 30 is such that the primary throttle valve must be moved to partially opened position before the secondary throttle valve is moved toward open position, though the movement of the primary throttle valve after the secondary throttle valve has started to open is sufficient to fully open the secondary throttle valve. An arm 54 on lever 30 is adapted to engage lever 38 as the primary throttle valve is moved toward closed position and to positively move said lever in the direction to close the secondary throttle valve. The effective length of rod 44 in transmitting the closing movement of lever 38 to lever 40 may be adjusted by moving nuts 55 and 56 upwardly or downwardly on rod 44, nut 56 being used to lock nut 55 in place after an adjustment has been made.

Lever 40 through arm 58 is connected to a dashpot 60 to retard the opening movement of the secondary throttle valve until the engine has had sufficient time to respond to the opening of the primary throttle valve. This arrangement gives a higher air velocity for engine acceleration and a larger volume of fuel-air mixture for high power output and speed after acceleration. The dashpot, which may be built integrally with the carburetor, using fuel from the fuel bowl as the hydraulic fluid, is shown mounted on the side of the carburetor as a self-contained unit, consisting of cylinder 62 and a piston 64 connected to arm 58 by a rod 66. A calibrated orifice 68 is provided in piston 64 to permit the fluid beneath the piston to pass slowly to the space above the piston as the secondary throttle valve is urged to its open position by spring 48 after the primary throttle valve has been opened sufficiently to cause lever 30 to engage lug 52 and move lever 38 in the clockwise direction. A passage having a check valve 69 therein is provided in piston 64 to permit the rapid return of the secondary throttle valve to its closed position.

To prevent the secondary throttle valve from opening before the engine becomes warm, a bimetallic thermostatic element 70 having a finger 72 for engaging a lever 73 is provided to positively hold the throttle valve 20B closed while the engine is cold, lever 73 being rigidly secured to shaft 42 and adapted to rotate in unison with lever 40 and arm 58. The thermostat is disposed in a housing 74 and secured to the wall thereof by a rivet 76 or the like. Heated air from a stove or the like (not shown) adjacent the exhaust manifold of the engine is drawn by intake manifold vacuum through tube 78 around thermostat 70 in the housing and thence through tube 80 to the intake manifold 12. When the engine is cold, the free arm of the thermostat assumes the position shown in Figure 1 with finger 72 hooked over one end of lever 73, said end being beveled to permit the throttle valve 20B to close after the thermostat has moved to the position shown in Figure 1. As the engine becomes warm, the free arm of the thermostat moves to the right, as shown in Figure 2, sufficiently to free lever 73 and permit said lever and throttle valve 20B to rotate

unobstructed by said thermostat. Spring 48 which forms a yieldable connection between levers 38 and 40 permits the primary throttle valve to be moved to its wide open position while the secondary throttle valve is held closed by thermostatic element 70.

In the operation of the present carburetor, starting with the engine cold, the choke valve 24 will be closed and the secondary throttle valve will be held in its latched position by the finger 72 of thermostat 70 hooked over the end of lever 73. During the warm-up period, the primary induction system is the sole source of fuel-air mixture for the engine at part and wide open throttle operations, though during idling the idling systems of both the primary and secondary induction systems are in operation regardless of temperature. As the engine becomes warm, the heated air drawn from the stove around the exhaust manifold passes through housing 74, heating thermostat 70 and causing it to move in the direction to release lever 73. The choke valve, which is preferably of the automatic type, is also gradually opened as the engine becomes warm. After the engine has become fully warm and thermostat 70 is fully withdrawn from lever 73, the opening movement of the primary throttle valve beyond the point at which lever 30 engages lug 52 of lever 38 moves rod 44 downwardly, compressing spring 48, which in turn urges lever 40 in the direction to open the secondary throttle valve 20B. The opening movement of the throttle valve 20B is retarded by dashpot 60 so that the air flow through the primary induction passage will have time to increase to the amount corresponding substantially to the increased throttle opening before the secondary system becomes effective. When the primary throttle valve is moved toward closed position, arm 54 engages lever 38 and through rod 44 and lever 40 positively moves secondary throttle valve 20B toward closed position.

Many modifications may be made in the present device without departing from the scope of the present invention, for example, the thermostatic means for holding throttle valve 20B in its closed position may be of any other suitable type than that shown in the drawings, or said throttle valve may be controlled by the thermostat of the automatic choke. Further, while only one induction passage for each of the two systems is shown, each system may include a plurality of induction passages containing throttle valves actuated by a control mechanism such as the one shown in the drawings. Further modifications may be made to suit requirements.

I claim:

1. A carburetor for an internal combustion engine comprising a primary induction passage having a throttle therein, a secondary induction passage having a throttle therein, a means for positively opening said primary throttle, a linkage connecting said throttles and having a yieldable connection therein, and a dashpot for retarding the opening movement of said secondary throttle to permit the primary throttle to open fully before the secondary throttle has opened fully.
2. A carburetor for an internal combustion engine comprising a primary induction passage having a throttle therein, a secondary induction passage having a throttle therein, a linkage connecting said throttles and having a yieldable connection therein, a dashpot for retarding the opening movement of said secondary throttle to permit the primary throttle to open before the secondary throttle is opened, and a thermostatic means for

holding said secondary throttle closed when the engine is cold.

3. A carburetor for an internal combustion engine comprising a primary induction passage having a throttle therein, a manually actuated means for positively opening said primary throttle, a secondary induction passage having a throttle therein, a linkage connecting said throttles and having a yieldable means therein and including a lost motion connection to permit the primary throttle to open to a predetermined position before the secondary throttle is opened, and a dashpot for retarding the opening movement of said secondary throttle.

4. A carburetor for an internal combustion engine comprising a primary induction passage having a throttle therein adapted to be manually actuated, a secondary induction passage having a throttle therein, a linkage connecting said throttles and having a yieldable means therein and including a lost motion connection to permit the primary throttle to open to a predetermined position before the secondary throttle is opened, a dashpot for retarding the opening movement of said secondary throttle, and a thermostatic means for positively holding said secondary throttle in closed position when the engine is cold.

5. A carburetor for an internal combustion engine comprising a primary induction passage having a throttle therein, a lever for positively actuating said throttle, and a secondary induction passage having a throttle therein, a linkage including a means adapted to yieldably urge said secondary throttle in the opening direction as the primary throttle is opened, a lost motion connection between said linkage and said primary throttle lever, and a means for retarding the opening movement of said secondary throttle.

6. A carburetor for an internal combustion engine comprising a primary induction passage having a throttle therein, a lever for positively actuating said throttle, a secondary induction passage having a throttle therein, a linkage including a means adapted to yieldably urge said secondary throttle in the opening direction as the primary throttle is opened and to positively close the secondary throttle as the primary throttle is closed, a lost motion connection between said linkage and said primary throttle lever, and a dashpot for retarding the opening movement of said secondary throttle.

7. A carburetor for an internal combustion engine comprising a primary induction passage having a throttle therein, a lever for actuating said throttle, a secondary induction passage having a throttle therein, a linkage including a means adapted to yieldably urge said secondary

throttle in the opening direction as the primary throttle is opened, a lost motion connection between said linkage and said primary throttle lever, a means for retarding the opening movement of said secondary throttle, and a means responsive to engine temperature for holding said secondary throttle in closed position when the engine is cold.

8. A carburetor for an internal combustion engine comprising a primary induction passage having a throttle and a choke therein, a lever for actuating said throttle, a secondary induction passage having a throttle therein, a linkage including a means adapted to yieldably urge said secondary throttle in the opening direction as the primary throttle is opened and to positively close the secondary throttle as the primary throttle is closed, a lost motion connection between said linkage and said primary throttle lever, a dashpot for retarding the opening movement of said secondary throttle, and a means responsive to engine temperature for positively holding said secondary throttle closed when the choke in the primary induction passage is effective to restrict the flow of air therethrough.

9. A carburetor for an internal combustion engine comprising a primary induction passage having a throttle therein, a means for positively opening said primary throttle, a secondary induction passage having a throttle therein, a linkage connecting said throttles and having a yieldable connection therein, and a means for retarding the opening movement of said secondary throttle.

10. A carburetor for an internal combustion engine comprising a primary induction passage having a throttle therein, a secondary induction passage having a throttle therein, a linkage connecting said throttles and having a yieldable connection therein, a means for retarding the opening movement of said secondary throttle, and a means responsive to engine temperature for holding said secondary throttle valve closed when the engine is cold.
